UNITED STATES PATENT OFFICE.

REINHOLD HAKEWESSELL, OF HARTFORD, AND EDWIN C. HENN, OF BLOOMFIELD, CONNECTICUT.

METAL-WORKING MACHINE.

SPECIFICATION forming part of Letters Patent No. 655,974, dated August 14, 1900.

Application filed December 9, 1899, Serial No. 739,828. (No model.)

To all whom it may concern:

Be it known that we, REINHOLD HAKEWESSELL, a resident of the city of Hartford, and EDWIN C. HENN, a resident of Bloomfield, in 5 the county of Hartford and State of Connecticut, citizens of the United States of America, have invented certain new and useful Improvements in Metal-Working Machines, of which the following is a specification.

10 This invention relates, generically, to metal-working machines, and more specifically to automatic screw-making machines of that class embodying means whereby a series of screw-rods may be independently operated upon simultaneously by independent tools having separate and distinct functions and wherein means are provided for automatically presenting each screw-rod of the series after being operated upon by one tool to the 15 action of the next adjacent tool and successively to the remaining tools of the series, whereby a plurality of screw-rods will undergo separate and distinct operations simultaneously and whereby after the first complete cycle of operations of the machine one 20 screw will be completed at each successive operation of the tools.

An object of this invention is to provide, in connection with the spindle-carrying turret 25 and reciprocating main tool-carrier, improved differential-speed actuating mechanism embodying means for imparting a slow advancing movement to the main tool-carrier and concurrently retaining the turret at rest and 30 for imparting a relatively-rapid retracting movement to the main tool-carrier and simultaneously imparting a rapid rotative movement to the turret, whereby to bring each rod-carrying spindle into position to be operated upon by the next tool of the series, which 35 is an improvement of extreme importance in this class of machines, as it materially lessens the time required in the making of screws and analogous articles.

40 With this object in view the invention consists in certain improvements and in certain novel details in the construction and organization of the several parts of the screw-making machine, as will be hereinafter more 45 fully described, and set forth in the claims.

In the drawings accompanying and forming

a part of this specification, Figure 1 is a plan view of a screw-making machine embodying this invention, the main tool-carrier being shown in a partially-retracted position. Fig. 55 2 is a side elevation of the machine looking in the direction of the arrow, Fig. 1. Fig. 3 is a rear elevation, on a larger scale, of the turret, rod-carrying spindles, and a portion of the spindle and turret actuating mechanism, with a portion of the framework of the machine, the spindles being shown in section. Fig. 4 is a right-hand side elevation of the parts shown in Fig. 3. Fig. 5 is a side elevation of a portion of the framing, the main 60 tool-carrier, and the mechanism which directly controls the rotation of the tools and the rotation of the rod-carrying spindles. Fig. 6 is an end view of a portion of the mechanism shown in Fig. 5. Fig. 7 is an end view, 70 partially in section, of the machine as seen from the left in Figs. 1 and 2, the section being taken on the dotted angular line Yz , Fig. 9, the turret being shown locked, with the spindles in proper aligned position with relation to the tools, and the turret-rotating sector or fan-wheel being shown out of engagement with the spur-gear of said turret. Fig. 75 8 is a sectional end view, similar to Fig. 7, of a portion of the machine, the section being taken on the straight dotted line xy , Fig. 9, and showing the parts in positions differing from those shown in Fig. 7. Fig. 9 is a plan view of the turret-casing detached. Fig. 80 10 is a plan view, on a large scale, of a portion of the spindle-carrying turret and main tool-carrier, showing in connection therewith the auxiliary vertically-movable tool-carrier. Fig. 11 is a side elevation of the parts shown in Fig. 10 looking in the direction of the arrow, Fig. 1. Fig. 12 is a plan view of a portion of the turret and main tool-carrier and shows, in connection with the frame, the adjustable stop for gaging the position of the screw-rod. Fig. 13 is a side elevation of the 85 parts shown in Fig. 12. Fig. 14 is a plan view, on a larger scale, of a portion of the machine, including a portion of the differential-feed mechanism which controls the movements of the turret, main and auxiliary tool-carriers, 90 and certain other parts of the machine. Fig. 15 is a sectional view taken on dotted line w 95 100

w, Fig. 14, looking in the direction of the arrow in said figure. Figs. 16 and 17 are plan and end views, respectively, on an exaggerated scale, of the differential-speed-mechanism clutch. Fig. 18 is an enlarged longitudinal section of one of the screw-rod spindles and the clutches and other controlling devices in connection therewith. Fig. 19 is a side view of the parts shown in Fig. 18. Fig. 20 is a sectional view, on a large scale, of a portion of the main tool-carrier and the screw-threading instrumentalities excluding the die. Fig. 21 is an enlarged cross-sectional view of the parts shown in Fig. 18, taken on the line *u u* and looking in the direction of the arrow. Fig. 22 is a side view, partly in section, of the parts shown in Fig. 21 as seen from the left in said figure. Fig. 23 is an end view of a portion of the die-carrying head as seen from the left in Fig. 20. Fig. 24 is a plan view of a portion of the machine, on an enlarged scale, showing a portion of the screw-threading mechanism and also showing the screw-threading-device starter and the means for controlling the movement thereof. Fig. 25 is an end view of the parts shown in Fig. 24, said figure being drawn in projection with Fig. 24. Fig. 26 is a side elevation of a portion of the machine as seen from above in Fig. 1 and showing the devices which control the operation of the rod-spindle clutch. Fig. 27 is a side view, partly in section, on a large scale, of a portion of the turret and main tool-carrier and showing in connection therewith a modified form of screw-threading device and means for actuating said device, the tool-carrier being shown in a retracted position; and Fig. 28 is a view similar to Fig. 27 of the same parts, showing the tool-carrier in an advanced position or in the position it occupies after the screw-thread has been formed on the screw-rod and the chasers of the die have been released from said rod.

Similar characters designate like parts in all the figures of the drawings.

Briefly stated, the screw-making machine embodies, in part, the following co-operative instrumentalities, which are so constructed and organized and are so timed in their movements as to automatically produce screws or analogous articles, namely: a main tool-carrier supported for horizontal reciprocatory movements and including a series of tools, mechanism for independently rotating one or more of said tools intermittently, a work-spindle carrier or turret having a horizontal axis and having a series of horizontal spindle-sockets, a series of rod-carrying spindles embodying rod clamping and releasing means and supported for rotation in said turret, means for rotating said spindles, improved means for intermittently advancing and for limiting the advancing movement of successive screw-rods, differential-speed actuating mechanism for imparting slow advancing movements and a relatively-rapid return movement to the main tool-carrier and for

imparting rapid step-by-step rotative movements to the turret concurrently with the return movements of said carrier, means automatically operative at predetermined points in the orbital movements of the spindles for independently and successively adjusting said spindles to center them successively with respect to a tool or tools of the main tool-carrier, a supplemental tool-carrier supported for movement transversely and longitudinally of the screw-rod, means controlled by the main tool-carrier for advancing and retracting the supplemental tool-carrier concurrently with the advancing and return movements, respectively, of said main tool-carrier, an improved screw-threading device, a screw-threading-device starter disposed in position for imparting an advancing movement to the screw-threading device independent of the movement of the main tool-carrier, and means for actuating said starting device at a predetermined point in the advancing movement of said carrier.

The framework of the machine may be of any suitable construction for carrying the several parts, and in the form shown in the drawings consists of a bed *B*, composed of suitable side rails and end rails supported on legs in the usual manner, said legs resting on an oil-pan, as in machines of this class.

Supported in ways on the bed *B* for horizontal movement is the main tool-carrier *B'*, having a series of tool-carrying spindles, as 100 2, 3, and 4, supported therein and preferably equidistantly disposed about a common center, one or more of said tool-spindles having means, as hereinafter described, whereby the same may be rotated.

The rod or work-spindle carrier or turret *D*, which will be hereinafter referred to simply as the "turret" or "spindle-carrier," is shown rotatably supported in a horizontal bearing in a turret-casing *5*, shown flanged 110 at its base and bolted to the bed *B* of the machine near the forward end thereof or at the left-hand end of the machine, as shown at Figs. 1 and 2. Formed around and in parallelism with the axis of said turret is a series 115 of sockets or bearings, in each of which is journaled a tubular rod-carrying spindle *6*, each spindle being adapted for carrying a screw-rod or piece of work to be operated upon by the tools of the main tool-carrier, 120 means being provided, as hereinafter described, for clamping, releasing, and advancing the screw-rod.

In the drawings (see Figs. 2, 3, 4, 7, 8, 18, and 19) the turret is shown having four spindles supported for rotation in the turret at equal distances about a common center. These spindles, which may be duplicates of one another, are each furnished with a driven pinion *7*, fixed thereto, as shown in Figs. 3 130 and 4, and are simultaneously rotated by a driving-pinion *8*, secured to the forward end of a spindle-actuating shaft *E*, which shaft is journaled at its forward end in the turret

and at its rear end in a bearing 9, forming part of the bed of the machine, said shaft extending through the center of the main tool-carrier (see Fig. 5) and being driven at 5 the proper speed through the medium of the main driving-shaft 10, which is operatively connected to the spindle-actuating shaft by a suitable train of gears G, said driving-shaft being furnished with a pulley, which may be 10 driven from any suitable source of power.

The spindle-carrier or turret D may be constructed to carry any desired number of spindles, and the main tool-carrier B' may likewise be constructed to carry a corresponding 15 or any desired number of tools, the number of spindles and tools depending of course on the number of operations required to complete the piece of work.

Through mechanism hereinafter described 20 the rod-spindles not only have a rotative movement about their own axes, but also have intermittent orbital movements about a common center. These intermittent or step-by-step orbital movements are imparted to the 25 rods-spindles for the purpose of bringing the rods carried thereby successively into positions to be operated upon by the successive tools of the main tool-carrier.

In practice the turret D will be locked in a 30 fixed position and held stationary during the advancing or working movement of the main tool-carrier, and for the purpose of saving time in the operation of forming the screws it is desirable that the main tool-carrier shall 35 have a slow advancing movement and a rapid return movement and that the turret D shall have a rapid rotative movement concurrently with the return movement of the carrier—that is to say, the main tool-carrier and turret 40 shall be so constructed and timed in their movements that the time occupied in the retractive movement of the tool-carrier and the rotative movement of the turret shall be much less than that utilized in the advancing of 45 the tool-carrier or during the operation of the tools upon the rod or while the turret is held stationary—and to accomplish this end there is provided in connection with the main tool-carrier a turret differential-speed actuating mechanism, (designated as a whole and 50 in a general way by H, see Figs. 14 and 15,) the construction, organization, and operation of which will be hereinafter fully described.

The differential-speed-actuating mechanism, (see Figs. 1, 14, 15, and 16,) which practically controls the movements of the turret, main tool-carrier, the rod clamping, releasing, and feeding devices, and the supplemental tool-carriers, preferably comprises a cam-shaft F, journaled in suitable bearings in the framework below the bed B; a fan-wheel or sector 12, fixed to said shaft; a spur-wheel 13, fixed to the outer end of the turret D in position to be intermittently engaged and rotated by the fan-wheel; a cam C, carried by the cam-shaft F and having cam faces or straps 14 and 15 in position and adapted for

engaging a pin 15', fixed to the base of the main tool-carrier, (see Fig. 2;) an intermediate shaft 16, journaled at its ends in suitable 70 bearings in the framework, preferably above the cam-shaft F; a worm-wheel 18, fixed to the cam-shaft; a worm 19, fixed to the transverse shaft and meshing with said worm-wheel; two spur-wheels 20 and 21 of different diameters loosely mounted upon the intermediate shaft 16; a supplemental driving-shaft 22, journaled in brackets fixed to the framework of the machine; a pinion 23, fixed to said supplemental shaft 22, near one end 80 thereof, and meshing with the larger gear 20, which is loosely mounted on the intermediate shaft 16; a spur-wheel 24, fixed to the opposite end of said supplemental shaft and meshing with the smaller spur-wheel 21, which is 85 loosely mounted on the intermediate shaft 16; a clutch C', keyed to the shaft 16 between the two spur-wheels 20 and 21 and adapted for first locking one and then the other of said spur-wheels to said shaft; a clutch-actuator 90 (designated in a general way by I, see Figs. 14 and 15) constructed and organized to automatically shift the clutch C' first in one and then in the opposite direction at predetermined points in the rotation of the cam-shaft 95 F, whereby to effect first a slow rotation of the cam-shaft and then a relatively-rapid rotation of said shaft, and driving mechanism in connection with the supplemental driving-shaft 22, which in the present instance is 100 shown as a train of intermeshing bevel-gears G', one of which is fixed to said supplemental shaft and the other of which is fixed to a power-shaft 25, to which a pulley 26 is secured and which pulley may be driven by a 105 belt by any suitable power shown.

It is not desired to limit this invention to the particular construction and organization of differential-speed actuating mechanism shown in the accompanying drawings, as these 110 may be modified somewhat without departure from this invention.

The clutch C' is shown (see Figs. 15, 16, and 17) as a pin-clutch of novel construction, having pins at opposite ends thereof adapted for 115 engaging pins fixed in the inner adjacent faces of the hubs of the spur-wheels 21, which are loosely mounted on the intermediate shaft 16, the novelty in the construction of this pin-clutch consisting in so supporting the 120 pins that when they strike the pins carried by one or the other spur-wheel hubs said pins will yield laterally and obviate the injurious impact occurring in pin-clutches of ordinary construction. To accomplish this end, one 125 end 27' of the main body 27 of the pin-clutch, which is grooved circumferentially to form a seat for the shifting lever 28, has an annular groove 29 formed in the end face thereof to receive the series of spiral springs 30, preferably three in number, one end of each spring having a bearing against a pin 31, fixed to the recessed portion 27, and the other end of which spring bears against a pin 32, fixed to a cap 130

or plate 33, so connected to the portion 27 as to be capable of rotary movement with respect to said parts 27, and which cap 33 has an outwardly-projecting pin 34 fixed thereto in position and adapted for engaging the pin 35, carried on the hub of the loose spur-wheel, as will be understood by reference to Figs. 15, 16, and 17 of the drawings.

The cap or plate 33 may be held in operative relation with the portion 27 of the clutch C' in any suitable manner; but in the simplified organization thereof shown in Figs. 16 and 17 said cap is assumed to be held against displacement with relation to said portion by friction between pins 31 and 32, due to the endwise thrust or stress of the springs 30 against said pins, as will be readily understood.

As a simple means for actuating the clutch C' at predetermined points in the rotative movement of the cam-shaft F a clutch-actuator is provided, which preferably comprises a weighted bell-crank lever pivoted at 36 on a bracket 37, secured to the framework, one arm 28 of which engages in the circumferential groove of the clutch C' and the other arm 38 of which extends inward and terminates at a point above the cam-shaft F at the rear end of the machine, a cam 40, fixed to said cam-shaft and having two actuating abutments 41 and 42, respectively, the one 41 of which is so located on the cam 40 as to strike the arm 38 of the clutch-actuator and shift the clutch into engagement with the

spur-wheel 21 to effect a rapid rotation of the worm 19 and cam-shaft F immediately after the tools of the main tool-carrier have completed their operation, and thus impart a quick return movement to said carrier and a quick rotative movement to the turret. (See Figs. 14 and 15.) The clutch-actuator also embodies a curved supplemental lever 43, which is pivotally supported at one side of the arm 38 and has one end thereof in position to be actuated by the abutment 42 of the cam 40 and has its opposite end in position to engage a projection on and impart an opposite cam-shifting movement to the arm 38 of the bell-crank lever of the clutch-actuator when said lever 43 is actuated by the abutment 42 and is thrown outward thereby. (See Fig. 14.) In other words, the arm 38 of the bell-crank lever and the lower end of the lever 43 are normally in effective engagement and are reciprocally operative for actuating each other, whereby their cam-engaging ends will be brought alternately into operative relation with the cam-abutments 41 and 42, respectively. On the operation of the arm 38 by the cam-abutment the clutch C' will be shifted into effective engagement with the high-speed gear 21 and the abutment-engaging end of the lever 43 will concurrently be thrown into position to be acted upon by the abutment 42, the weight 44 accelerating the movement of these parts, and on the actuation of the lever 43 by the abutment 42 of the cam 40 the op-

posite end of said lever striking the projection on the arm 38 forces this arm with its non-weighted end into position to be operated by the abutment 41 of said cam and at the same time shifts the clutch C' into effective engagement with the low-speed gear 20, thus imparting, through the medium of the worm 19 and worm-wheel 18, a slow movement to the cam-shaft and a corresponding slow movement to the main tool-carrier, the fan-wheel 12, which actuates the turret, being during this slow movement of the carrier out of engagement with the spur-wheel 13, and the turret 80 is held stationary by means which will be hereinafter more fully described.

In practice (see Fig. 15) the abutments 41 and 42 will be so disposed circumferentially with respect to each other on the cam 40 that the clutch C' will be held in operative engagement with the low-speed gear 20 for about four-fifths of a complete rotation of the cam-shaft F, so that the time required for returning the tools to their normal ineffective position will be about one-fifth of that utilized in the operation of said tools.

To correct any misalignment or disarrangement of the rod-spindles with relation to the tool or tools which are to operate on the rod, which may result from various causes, as by one spindle wearing more than another, distortion of the spindle or spindle-carrier due to atmospheric influences or by the springing or warping of the framework, &c., there is provided in operative connection with the turret and operative independent of the turret-rotating means proper spindle-adjusting mechanism automatically operative for shifting the turret rotatably and in a direction contrary to the direction in which said turret is rotated by the differential-speed-actuating mechanism after each intermittent rotary movement thereof to bring the spindles successively to an accurate working or aligned position with relation to a tool and for locking the turret after the spindle is in a true adjusted position.

The means for shifting the turret, as above described, to adjust the spindles to correct working position and also for temporarily locking said turret in this adjusted position is shown comprising (see Figs. 7 and 8) two coöperative stop members s and s' and a turret shifting and locking member r. One of said stop members, as s, is shown as a screw adjustably seated in a bearing formed in a transverse shouldered portion, being formed by recessing the periphery of said turret, as at 45'. The head of the stop member s (which stop member will for convenience be termed a "stop-abutment") is extended beyond the face of the shouldered portion 45' in position to coöperate with the other stop member s'. This other stop member s' is shown as a reciprocating member, herein termed a "stop," supported in a horizontal bearing 46 on the turret-casing and is furnished with a spring for projecting the same into the path of the

stop-abutment s concurrently with the arrival of the stop-recess $45'$ adjacent said stop s' , as will be readily understood.

The number of stop-abutments s will correspond with the number of spindles mounted in the turret, there being four stop-abutments shown in the present instance, one between each pair of spindles, and there being one stop s' common to and successively coöperative with all said stop-abutments, the stop-receiving recesses being perfectly equidistantly disposed about the periphery of the turret. The two stop members s and s' will determine the working position of each spindle, the stop s being adjusted in or out, as required, to determine the extent of the rotary adjustment of the turret, and consequently the working position of each spindle.

The turret shifting or locking member r is shown in the nature of a bolt seated for longitudinal movement in a bearing 47 , extending outward from that side of the turret-casing opposite to that on which the bearing 46 is formed and having a wedged-shaped or beveled inner end which coöperates with a beveled portion of a lock-notch formed in the periphery of the turret. Each lock-notch, there being four shown, is disposed, preferably, central between two rod-spindles and are of considerably greater width in the direction of rotation of the turret than is the wedge portion of the turret shifting and locking bolt r , for various reasons.

As will be understood by reference to Figs. 7, 8, and 9, the series of lock-notches of the turret and the series of recesses $45'$ are not disposed exactly opposite to each other, but are located, respectively, at different points in the length of the turret.

As a means for actuating the turret-shifting bolt and for preventing an advancing movement of said bolt until the stop s' is in an advanced position there is provided bolt-actuating means which consist, preferably, of a bolt-retracting lever 48 , pivoted intermediate its ends on the framework and having the lower end thereof extending over the cam-shaft F , a disk or plate 49 , fixed to the cam-shaft F , a spring 50 , secured to the upper end of the lever 48 and exerting a bolt-advancing stress, and two cam-faced lever-actuating members 51 and 52 , carried on the disk 49 in position for actuating said lever and for holding the same in a retracted position the proper length of time.

In operation the bolt r is first released from the turret and the turret is shifted by the cam-wheel or sector to bring the spindles into approximate working position, the stop-abutment then being in position to engage the stop s' , which is at this time in the position shown in Fig. 7, after which the bolt r is advanced by the spring and its wedged portion engages the coöperative wedge face of the lock-notch, which shifts the turret in a reverse direction until the stop-abutment tightly engages the stop, which stop and bolt

prevent further movement of the turret in either direction.

Each rod-spindle (see Figs. 18 to 21, inclusive) preferably comprises in part a rotary chuck-sleeve 52 , supported in the turrets and having at the inner working end thereof an internally-flared chuck-compressing head 53 and a compressible collet or chuck 54 , supported for reciprocatory movement within said sleeve, and having a tapered face coöperative with the internal face of the head 53 , whereby the same is compressed to clamp the rod.

As a means for actuating the chuck to clamp the rod R there is provided chuck-actuating means shown consisting of a tubular thrust member 55 , supported for reciprocatory movement in the sleeve 52 , with its outward end in position for engaging the inner end of the chuck, whereby to advance the same to its clamping position, and having at the opposite end thereof a collar, a pair of thrust-rod-actuating fingers 56 and $56'$, pivotally supported on arms fixed to a collar 57 , secured to this end of the sleeve 52 , each of which fingers are somewhat L-shaped and have their outer ends in engagement with the outer end of the collar of the thrust member, a groove-collar 60 , loosely mounted upon the sleeve 52 for reciprocatory movement and having a conical end which coöperates with the inner ends of the fingers 56 and $56'$ and which is adapted for spreading the ends to impart a forward movement to the thrust member, an actuating-lever 61 , pivoted on the framework (see Fig. 2) and having a pin at the upper end thereof adapted to enter the groove in the collar 60 when this collar during the rotative movement of the turret arrives in coöperative relation with the lever, and a cam C^2 , fixed to the cam-shaft and having straps so constructed and arranged as to engage a pin $61'$ on and impart chuck opening and closing movements to the thrust member 55 immediately preceding and succeeding, respectively, the advancing movement of the rod R , which advancing movement of said rod is effected by means hereinafter described.

This means for feeding or advancing the screw-rod preferably consist of a clamp-sleeve 62 , supported within the tubular thrust member 55 and having at the outer end thereof a groove-head 63 , a clamp-sleeve actuator shown as consisting of a series of a pivotally-supported parallel-motion levers 64 , 65 , and 66 , the one 64 of which has a pin at the upper end thereof in position to enter the groove in the head 63 of the clamp-sleeve, as shown in Fig. 2, when the spindle of this clamp-sleeve arrives in a rod-feeding position, and cam-straps fixed to the cam C^2 and so disposed as to impart a rod-advancing movement to the clamp-sleeve immediately upon the release of said rod by the chuck 54 and for retracting said sleeve immediately after the chuck reclamps said rod.

In some cases, as when the threading de-

vice shown in Figs. 1, 2, and 20 is used, it is desirable to hold the rod stationary during the threading operation, and to accomplish this there is provided in connection with each 5 spindle a friction-clutch C³, which in the preferred form thereof shown (see Figs. 18 and 21) comprises a recessed driving clutch member 67, preferably formed integral with the pinion 7, loosely mounted on a collar 68, fixed 10 to the sleeve 52 of the spindle; a sleeve-like driven clutch member 70, splined to the collar 68; two expansile ring-sections or springs 69 and 69', concentrically disposed about the inner end of the member 70, within the recess 15 of the driving member 67, and two levers 71 and 72, having cam-like working faces disposed between adjacent ends of and in position to expand the ring-sections 69 and 69', the inner working end of said levers being 20 pivoted to the driven member 70, as indicated in Figs. 21 and 22, and the outer ends thereof being normally extended beyond the forward face of the member 67 in position to be pressed 25 inward by an actuator 67', splined for longitudinal movement upon the collar 68, and which actuator normally is held closely against the free ends of the ring-expanding levers by spiral springs 73, thus normally retaining the levers in ring-expanding position, 30 said springs abutting at their inner ends against the actuator (which is shown as a flanged collar) and at their outer ends against a flange 74 upon the collar 68. The springs 73, through the actuator 67', levers 71 and 72, and ring-sections 69 and 69', normally effect 35 a clutched engagement between the driving and driven clutch members and cause the spindle normally to be rotated.

As a means for retracting the actuator 67' 40 to release the two clutch members 67 and 70 automatically to stop the rotation of the spindle at the proper point in its orbital movement, there is provided a clutch-releasing device, which in the form thereof shown in 45 Figs. 2 and 26 comprises a lever 75, pivoted intermediate its ends on a bracket 76 and having at one end a pin or projection normally disposed in position to engage the inner face of the actuator 67' when the spindle 50 arrives in coöperative relation with the screw-threading device, and a lever 77, pivotally supported intermediate its ends on the frame and having its upper end in operative engagement with a crank-arm 78, fixed to the 55 pivot of the lever 75 and having at its lower end a pin in position to be operated by cam-straps on the cam C², whereby at the proper moment in the rotation of said cam an actuator-retracting movement will be imparted 60 to the lever 75, a stop or projection (not shown) on the outer face of the actuator 67' being thereby brought into position to engage a stop-abutment (not shown) which is fixed to the bracket and arrests the continued rotation of the rod-spindle until the lever 75 is 65 returned to its normal position, which return movement is effected by the counterweight

at the end of said lever 75 when the cam C² has arrived at the proper position to permit such movement.

7c

The screw-threading device shown in Figs. 1, 2, and 20 comprises a die-stock or tool-carrying spindle 2, seated for reciprocatory movement in a sleeve 80, journaled for rotation in a horizontal socket in the main tool-carrier B' and having a pinion 81, which meshes with a gear 82, (see Figs. 6 and 20,) fixed to the spindle-actuating shaft E, a pin-clutch comprising two members 83 and 84, the one 83 of which is carried at the forward 75 end of the sleeve 80 and the other 84 of which is carried at the forward end of the spindle or die-stock 2 and each of which has pins which on the forward movement of the main tool-carrier engage each other and cause the 80 spindle to rotate with the sleeve, a socket (see Fig. 20) being formed in the clutch member 84 of the spindle 2 to receive the shank or stem of the die.

On the retractive movement of the main 90 tool-carrier after the thread is formed the rod R, which was held stationary during the threading operation, is rotated to screw off the threading-die, the clutch members during this retractive movement of said carrier 95 being separated, so that the spindle 2 may be held against rotation by means hereinafter described.

In connection with the spindle 2 there is provided a retracting device operative on the 100 release of the screw-threading die from the rod for imparting a quick return movement to said spindle. This consists of a spiral spring 84', surrounding the rear end of the spindle and bearing at its forward end against a fixture 105 on the tool-carrier and at its rearward end against a bar 85, fixed to the rear end of said spindle. This bar 85 has a set of projecting pins 86 disposed to engage a yieldable stop member 87, secured to the tool-carrier at a 110 predetermined point in the retractive movement of the main tool-carrier, or at that point in the retracted movement of said carrier when the clutch-pins are released, thus acting to hold the spindle against rotation until 115 the die is released from the rod, after which the spring 84' imparts a quick return movement to said spindle.

In Fig. 1 of the drawings the die-stock or 120 spindle 2 is shown furnished with an ordinary screw-threading die of the "box" type.

In Figs. 27 and 28, which illustrate a modified form of screw-threading device, the die-stock or spindle 2 is shown furnished with a head 88, having a series of chasers 89, pivotally supported for radial movement in longitudinal grooves formed in said head and having their rear ends extended somewhat beyond the rear face of said head 88, and as a means for actuating the chasers a collar 90 125 is mounted upon the spindle 2 and has a conical outer end to coöperate with the adjacent ends of said chasers on a longitudinal movement of said collar, whereby to spread

these ends and close the chasers on the end of the screw-rod. The means for imparting a chaser closing and opening movement to the collar 90 in the form of device illustrated 5 in Fig. 28 consists of two pivotally-supported arms 91 and 92, respectively, the lower free ends of which engage opposite ends, respectively, of the collar, said arms being pivotally carried at their upper ends on a bracket 93, 10 fixed to the main tool-carrier. These arms 91 and 92 are alternately operated during the retractive and advancing movement of the main tool-carrier by means of pins 94 and 95, adjustably secured to a bar 96, fixed to the 15 turret-casing 5, the pin 94 being so located as to engage the pivoted arm 91 at a predetermined point in the retractive movement of the tool-carrier to effect a chaser-closing movement of the collar 90, and the pin 95 being 20 so located on the bar 96 as to strike the arm 92 and effect a chaser-opening movement of the collar 90 at a predetermined point in the advancing movement of said carrier. When this form of screw-threading device is 25 employed, the spindle 2 will be held against rotative movement during the screw-threading operation, while screw-rod R will be rotated, and for this purpose a collar 97 is shown fixed to the spindle and provided with a pin 30 which enters a hole in the main tool-carrier. (See Fig. 27.)

As a means for "starting" the screw-threading die upon the end of the rod after said die has arrived by the advancing movement of 35 the main tool-carrier in coöperative relation with said rod, there is provided a starting device, (designated in a general way by S,) consisting of a crank-arm 98, fixed to a crank-shaft journaled in a vertical bearing on a 40 bracket 99, fixed to the base of the main tool-carrier, and which shaft has at the lower end thereof another crank-arm 98', disposed substantially at right angles to the arm 98; a thrust-pin 100, adjustably secured in a bearing 45 at the free end of the crank-arm 98, with its forward end in alinement with and in position to strike the outer reduced end of the die-spindle 2; an abutment 101, adjustably seated in a bearing in the free end of the 50 lower crank-arm 102, fixed at one end to a projection on the starting device and at its opposite end to a fixture of the main carrier and adapted for normally retaining the starting device with the thrust-pin thereof out of 55 engagement with the spindle 2, and a starting-device actuator 103, fixed to the bed of the machine in the path of movement of the working end of the abutment 101 and adapted at a predetermined point in the advancing 60 movement of the main carrier for effecting a die-starting movement of the starting device, as will be readily understood by reference to Figs. 1, 24, and 25 of the drawings.

In addition to the main tool-carrier, which 65 is supported for movement longitudinally of the machine, there is provided a supplemental tool-carrier, (designated by T,) which is lo-

cated above and at one side of the rod-spindle-actuating shaft E and which is constructed and organized for adjustment toward and 70 from the turret and for movements in a plane intersecting the axis of said shaft E. This tool-carrier T comprises a slide-rest-supported on horizontal ways on a bracket 104, fixed to the turret-casing 5, (see Figs. 2, 10, and 11,) 75 and a tool-carrying slide, which constitutes the tool-carrier proper, mounted on said slide-rest for vertical movement, said slide being located between the turret and main tool-carrier and in such position that the tool carried 80 thereby may operate upon the screw-rod of one of the spindles, means, such as shown at 8c 105, being provided for adjusting the slide-rest horizontally.

As a means for advancing and retracting 85 the tool-carrying slide concurrently with the forward and backward movement of the main tool-carrier, there is provided a slide-actuator which, in the form shown in said Figs. 2, 10, and 11, consists of two horizontally-disposed 90 cam-straps 106 and 107, located one above the other, and one of which straps, as 107, has a cam-face 107', which coöperates with a projection on the slide and effects, on the advancing movement of the main tool-carrier, 95 an advancing movement of said slide, and the other of which, as 106, has a cam-face 106' disposed in proper position for engaging another projection on the tool-slide at a proper point in the retractive movement of the main 100 tool-carrier for imparting an upward or retractive movement to said slide, these cam-straps 106 and 107 being fixed at one end to an upright 108, secured to the main tool-carrier, as illustrated in these figures. 105

In addition to the main and supplemental tool-carriers the machine is preferably provided with two horizontally-movable tool-carriers, mounted, respectively, on the opposite side rails of the bed of the machine in position to operate upon the rods of the two lowermost spindles. These carriers, which are designated by L and L', may be furnished one with a turning-down tool and the other with a cut-off tool, and the tool-carrier T may be 110 furnished with a nurling-tool. The two tool-carriers L and L' will be actuated by cam-straps on a cam C⁴, fixed to the cam-shaft F, through the medium of levers 109 and 110, pivotally supported on the bed of the machine and connected at their upper ends to the tool-carriers L and L', respectively, as 115 will be readily understood. 120

For a more complete description of the friction-clutch herein described in connection 125 with the rod-spindle and the pin-clutch herein described in connection with the differential-speed actuating mechanism reference may be had to the applications serially numbered 739,775 and 739,776, respectively, filed concurrently with this application. 130

It is distinctly to be understood that the present application is not limited to any particular kind of clutch devices, as any suitable

form of clutch may be employed in connection with the differential-speed actuating mechanism or with the rod-spindles.

We claim—

5. 1. A metal-working machine embodying a bed; a tool-carrier shiftably supported on said bed; a turret supported for rotative movement; and differential-speed actuating mechanism in operative connection with the tool-carrier and turret and adapted for imparting slow advance and quick return movements to said carrier, and for imparting quick rotative movements to the turret concurrently with the quick return movements 15 of said carrier.
- 15 2. A metal-working machine embodying a turret supported for rotative movements; a tool-carrier supported for movements toward and from said turret; differential-speed 20 actuating mechanism in operative connection with the turret and carrier and effective for imparting quick rotative and quick return movements, concurrently, to the turret and carrier, respectively, and for imparting a relatively-slow advancing movement to 25 said carrier; and means for holding the turret at rest during the slow advancing movement of said carrier.
- 30 3. The combination with a carrier and a turret, supported for reciprocatory and rotative movements, respectively, of differential-speed actuating mechanism in operative connection with said carrier and turret and embodying instrumentalities imparting, alternately, slow advancing and quick return movements to said carrier and also for imparting quick step-by-step rotative movements to the turret concurrently with the quick return movements of the carrier; and 35 automatically - operative means for locking the turret concurrently with the arrival of the carrier at the end of its retractive movement and for holding the same against rotative movement during the entire advancing 40 movement of said carrier.
- 45 4. In a metal-working machine, the combination with a rotative turret and a reciprocatory tool-carrier; of differential-speed actuating mechanism embodying a high-speed train of gears and a low-speed train of gears; automatically - operative means for effecting an operative connection between the turret, carrier and high-speed train of gears concurrently, whereby simultaneously to impart quick rotative and quick return movements to the turret and carrier, respectively, and alternately for effecting an operative connection between the low-speed train and said carrier; and means for holding the 55 turret at rest while the carrier is being operated through the low-speed train.
- 60 5. The combination of a rotative turret; a reciprocatory carrier; differential-speed actuating mechanism embodying a high-speed and a low-speed train of gears the latter of which is intermittently effective for imparting a slow advancing movement to the car-

rier and the former of which is intermittently effective for imparting concurrent quick rotative and quick return movements 70 to the turret and carrier, respectively; and automatically - operative means for locking the turret against movement during the slow advancing movement of the carrier.

6. In a metal-working machine, the combination of a reciprocatory carrier; a rotative turret; carrier and turret actuating mechanisms including high and low speed devices alternately and automatically operating the carrier, and the high-speed device of which 80 is automatically effective for concurrently operating both the carrier and turret; and means for holding the turret at rest during the operation of the low-speed device.

7. The combination with a work - holder, 85 and with a tool-carrier supported for reciprocatory movements, of a tool-holder supported in said carrier for movements independent of said carrier; means for advancing and retracting said carrier; and a starting device 90 operative at a predetermined point in the advancing movement of said carrier for imparting an independent advancing movement to the tool-holder with relation to said carrier.

8. A screw-making machine embodying a 95 turret; a tool-carrier; a screw-threading device supported in said carrier for independent movements; means for imparting rotative movements to the turret and for advancing and retracting the carrier; rod-spindles supported in said turret; rotating mechanism for said rod-spindles; and a starting device 100 operable at a predetermined point in the advancing movement of the carrier for imparting an advancing movement to said screw-threading device independent of the tool-carrier.

9. In a screw-making machine, a reciprocatory tool-carrier, in combination with a screw-threading device supported in said carrier for independent longitudinal movement; a starting device pivotally supported on a part of said carrier and having an arm in operative relation with the rear end of the screw-threading device; a starting-device actuator supported on the frame or bed of the machine in the path of the starting device and adapted at a predetermined point in the advancing movement of the carrier for actuating said starting device to impart a slight advancing 110 movement to the screw-threading device with relation to said carrier.

10. A metal-working machine embodying a 115 multisindle turret supported for rotative movements; a tool-carrier supported for reciprocatory movements; differential - speed actuating mechanism in operative connection with the turret and carrier and effective intermittently for imparting concurrent quick rotative and quick return movements to the 120 turret and carrier respectively, and for imparting a relatively-slow advancing movement to the carrier alternately with said quick return movements; automatically-op-

erative locking means for holding the turret at rest during the advancing movement of the carrier; a plurality of rod-carrying spindles; a plurality of clutches in connection one with each spindle and embodying a driving and a driven member the latter of which is fixed to the spindle; resilient means normally for holding the clutch members in locked engagement; rotating means for the driving clutch member; clutch-releasing means disposed in the orbital path of the clutch mem-

bers; and automatic means for operating the clutch-releasing means at a predetermined point in the orbital movement of the spindles.
